United States Patent Office

Des. 204,499
Patented Apr. 19, 1966

204,499

JUG

Montgomery Ferar, Huntington Woods, Mich., assignor
to Hercules Powder Company, Wilmington, Del., a
corporation of Delaware

Filed Oct. 20, 1964, Ser. No. 82,240

Term of patent 14 years

(Cl. D58—5)

FIG. 1

FIG. 2

FIG. 3

FIG. 1 is a perspective view of a side and end of a jug embodying my new design;

FIG. 2 is a top plan view thereof; and

FIG. 3 is a side elevational view thereof.

The end and side of the jug not shown are substantially identical to the end and side shown in the accompanying drawing.

I claim:

The ornamental design for a jug, substantially as shown and described.
